Patented July 30, 1918.

FIG. 3

INVENTOR
John F. Smith
BY
Pierre Barnes
ATTORNEY

UNITED STATES PATENT OFFICE.

JOHN F. SMITH, OF SEATTLE, WASHINGTON, ASSIGNOR OF FIFTY-FIVE ONE-HUNDREDTHS TO HENRY B. BURKHART, OF SEATTLE, WASHINGTON.

OIL-BURNER.

1,273,942.

Specification of Letters Patent. Patented July 30, 1918.

Application filed December 26, 1917. Serial No. 208,741.

To all whom it may concern:

Be it known that I, JOHN F. SMITH, a citizen of the United States, residing at Seattle, in the county of King and State of Washington, have invented certain new and useful Improvements in Oil-Burners, of which the following is a specification.

This invention relates to burners for liquid hydrocarbons such as kerosene; and its object is to produce a burner of this character which will be economical in the consumption of fuel and efficient in operation.

The invention consists in the novel construction, adaptation and combination of parts, as will be hereinafter described and claimed.

In the accompanying drawings, Figure 1 is a side elevational view of apparatus embodying my invention applied to a stove which is shown in vertical section. Fig. 2 is a horizontal sectional view through 2—2 of Fig. 1. Fig. 3 is a vertical sectional view of the burner proper, said section being taken through 3—3 of Fig. 2.

The burner is shown as applied within the combustion chamber A of a heating stove B. The burner consists in a head comprising a plurality of hollow arms 5 having orifices 5¹ in their undersides and extending radially from the upper end of a tubular post 6 which extends through and is rigidly secured to a plate 7 which serves as the floor of said combustion chamber.

The lower end of the post 6 is coupled, as by an elbow 8, with a horizontally disposed pipe 9 which affords the mixing chamber of the device. Within the combustion chamber A and about the post 6 is coiled a vaporization tube 10 which is connected from its lower end by tubes 11 and 12 with the lower end of a fuel-oil supply tank 13. Included in said tube connections is a regulating valve 14.

The upper end of said coil is extended in the nature of a loop 15 over the top of the burner, as shown in Figs. 1 and 2, and thence the tube extends downwardly, as at 16, through the floor plate 7. Below the latter the tube part 16 is connected by a tube 17 with a needle valve, indicated by 18, having its discharge nozzle 19 arranged in axial alinement with the axis of the pipe 9 and, preferably, at a short distance from the outer end of the same.

Vaporized oil is emitted from the valve

nozzle 19 into the interior of the pipe 9 to mix with air which is sucked into the latter through the space between the pipe end and said nozzle. The quantity of air thus admitted into the pipe may, however, be regulated by adjustably moving a sleeve 20 provided on the pipe toward or from the nozzle to correspondingly lessen or increase the effective air inlet opening.

The tank 13 is first partly filled with kerosene or other suitable oil through an opening which is closed by a plug 21. Air under pressure is then introduced into the tank through the pipe connection 22.

To use the burner, a small quantity of oil is poured upon the floor plate 7 and lighted by the operator through the stove door opening 23. The oil thus burned in the combustion chamber A will effect the heating of the vaporization coil 10, and the valve 18 is partly opened and the valve 14 fully opened, whereupon fuel oil is forced into the tubes by air pressure obtaining in the tank 13.

The oil in said tubes will be converted into a gas to be discharged therefrom through nozzle 19 into the pipe 9 wherein it mixes with air to form a combustible mixture which escapes through the various burner orifices in the form of flames. The flames are directed downwardly, soon rendering the tube coil 10 very hot with an increased rate of gas generation which is accommodated by opening valve 18 to a greater extent.

As the burning proceeds, the valve 18 is regulated until blue and steady flames are produced.

It is to be noted that the oil from the tank enters the lower end of coil 10 in which the vaporization occurs and the gas thus formed passes from the upper end of the coil into the loop 15 to be superheated before escaping into the mixing chamber provided by the pipe 9.

What I claim, is—

1. In apparatus of the class described, the combination with a burner having a head formed with a plurality of hollow arms having orifices in their undersides, a subjacent mixing chamber, and a hollow post connecting the latter with said head, of a tubular vaporizing coil surrounding said post, a connection for the supply of fuel oil under pressure to the lower end of said coil, an

outlet connection for gas from the upper end of said coil, and a needle valve provided on the discharge end of said outlet connection and arranged to deliver the gas into the 5 aforesaid mixing chamber.

2. In apparatus of the class described, the combination with a burner having a head formed with a plurality of hollow arms having orifices in their undersides, a subjacent 10 mixing chamber, and a hollow post connecting the latter with said head, of a tubular vaporizing coil surrounding said post, a connection for the supply of fuel oil under pressure to the lower end of said coil, an outlet 15 connection for gas from the upper end of said coil, said outlet connection being extended above the burner head to serve as a gas superheater, and a needle valve provided on the discharge end of said outlet connection 20 and arranged to deliver gas into the aforesaid mixing chamber.

3. In apparatus of the class described, the combination with a burner having a head provided with discharge orifices in its under- 25 side, an upright hollow post supporting said head, and a horizontal pipe affording a mixing chamber and connected to the lower end of said post, an oil vaporizing coil surrounding said post below said head, means

to supply oil under pressure into the lower 30 end of the coil, an outlet connection from the upper end of said coil, a valve provided on the discharge end of said connection, said valve being located to have its discharge 35 nozzle in axial alinement with and at a distance in front of the end of said pipe, and adjustable means provided on the latter to serve as an extension thereof for regulating the length of the effective gap through which air is admitted into the pipe. 40

4. In combination, a gas burner having an upright tubular post, a head provided with a plurality of arms provided on the upper end of said post, said arms being provided with orifices in their undersides, a gas and 45 air mixing pipe connected to the lower end of said post, an oil vaporizing coil provided below said head, means to supply oil under pressure to said coil, and manually regulated means to discharge the gas generated in said 50 coil into said pipe.

Signed at Seattle, Washington, this 17th day of December, 1917.

JOHN F. SMITH.
